UNITED STATES PATENT OFFICE.

ANTON PEARSON AND DAVID N. LINDQUIST, OF LINDSBORG, KANSAS.

MILK CARD.

Application filed July 13, 1926. Serial No. 122,318.

This invention relates to milk cards, an object of the invention being to provide a milk card which can be placed in a window or at other convenient location to advise the milkman as to the desire of the customer both as to the quantity of the milk and cream to be left.

A further object is to provide a milk card having suitable information printed thereon together with an improved indicator movable on the card and adapted to register with the data on the card.

A further object is to provide a card of this character which, while it is especially adapted for use in connection with the delivery of milk, cream, etc., may of course be adapted for other uses, and which is of extreme simplicity in construction and can be manufactured and sold at an extremely low price so that it may be distributed without cost to the customer and give real advertising value to the dealer and also result in great convenience to all parties.

With these and other objects in view, the invention consists in certain novel features of construction and combinations and arrangements of parts which will be more fully hereinafter described and pointed out in the claim.

30 In the accompanying drawings—

Figure 1 is a plan view in elevation of our improved device;

Figure 2 is a view in transverse section on the line 2—2 of Figure 1.

35 1 represents a card, which may be of paper, metal, or any other material. On this card 1 we preferably illustrate the outline of a milk pail, as shown at 2, and form centrally of the card 1 alined slots 3, said slots, however, being spaced apart so as to prevent undue weakening of the card.

40 We of course do not limit ourselves to the particular printed matter on the card but for purposes of illustration we have shown the card as having numerals 4 on one side of each slot, with printed matter 5 to illustrate the quantity on the other side of each slot.

In connection with our improved card

we employ an improved indicator 6, and in the specific form shown we employ two of these indicators 6, which are precisely alike and mounted to move in the slots 3, respectively.

Each indicator comprises a strip of material, which may be of spring metal or other suitable material which will perform the functions necessary. These strips are bent at two points intermediate their ends forming a bar 7 located at the back of the card 1 with the extremities of the strip projected through the slot and then bent at right angles, lying against the face of the card and forming clamps 8. In other words, this indicator has a crossbar 7 at the back of the card which has clamping members at both ends engaging the card at both sides of the slot, and these clamps, or rather the free ends of these clamps, constitute pointers and are adapted to register with the printed matter on the card to indicate the quantity of milk and cream or other goods desired. These indicators can be moved longitudinally of the slots 3 to register with the data thereon, and the milkman will know just what the customer desired to be left.

Various slight changes and alterations might be made in the general form of the parts described without departing from the invention, and hence we do not limit ourselves to the precise details set forth but consider ourselves at liberty to make such slight changes and alterations as fairly fall within the spirit and scope of the appended claim.

We claim:

45 A card of the character described having on its face the outline of a milk bottle and having a slot located within the confines of the outline of the bottle and having printed matter within the confines of the bottle outline at opposite sides of the slot, and a double pointer movable in the slot and adapted to register with the said printed matter.

ANTON PEARSON.
DAVID N. LINDQUIST.
